UNITED STATES PATENT OFFICE.

JAMES W. CAIN, OF DETROIT, MICHIGAN.

AUTOMOBILE-RADIATOR.

1,292,576.

Specification of Letters Patent. Patented Jan. 28, 1919.

Application filed March 3, 1913, Serial No. 751,847. Renewed November 7, 1916. Serial No. 130,061.

To all whom it may concern:

Be it known that I, JAMES W. CAIN, a citizen of the United States, residing at Detroit, in the county of Wayne and State of Michigan, have invented certain new and useful Improvements in Automobile-Radiators; and I do hereby declare the following to be a full, clear, and exact description of the invention, such as will enable others skilled in the art to which it appertains to make and use the same.

My invention has for its object to provide certain improvements in the frame structures of automobile radiators, and to such ends, the invention consists of the novel devices and combinations of devices herein-after described and defined in the claims.

In the accompanying drawings which illustrate the invention, like characters indicate like parts throughout the several views.

Referring to the drawings,

Figure 1 is a view in rear elevation with some parts broken away and some parts sectioned showing an automobile radiator embodying my invention;

Fig. 1^a is a detail section, showing the manner in which the sub-frame is secured to the water legs of the upper tank 2.

Fig. 2 is a side elevation of the parts shown in Fig. 1, some parts being broken away;

Fig. 3 is a detail view in perspective with parts sectioned on the line x³ x³ on Fig. 1;

Fig. 4 is a view corresponding to Fig. 3 but with the core partly removed from the radiator frame proper;

Fig. 5 is a detail view in perspective with parts sectioned on the line x⁵ x⁵ on Fig. 1.

In the drawing I have illustrated a radiator 1, which is of the usual form. The upper water tank 2 includes, as is usual, the water legs 2^a and the lower tank 3 is connected to the upper tank by a core which includes vertical tubes 4 and radiating fins 5.

These tanks and core, assembled in the manner described, are placed within the radiator frame 1 in the usual manner, abutting at the front side of the frame against the flange 1^a. This radiator frame 1 is provided at its rear portion with a flange 1^b, for a purpose which will later appear, and with the usual beading 1^b.

In order that the strain may be taken off the radiator core, so that it will not be broken or twisted when it is removed from

the radiator frame 1, I have provided strengthening elements which are arranged on opposite sides of the core. These elements, which are denoted generally by the reference character 6, are of general U-form in cross-section, as disclosed in Fig. 1^a of the drawing and extend from the water legs of the upper tank 2 to the lower tank 3. They are secured by soldering or otherwise as at 6^a to the upper tank and to the lower tank in a similar manner as at 6^a. The channel members 6, however, are unsecured to the core, but closely embrace the ends of the fins thereof, so as to prevent any movement of the same. Thus the upper and lower tanks will be rigidly supported by the strengthening elements 6 and all of the strain will be taken off of the core. These strengthening elements are provided with portions 6^b which are bent back upon the sides of the channel portions and are provided with flanges 6^c, as clearly disclosed in Fig. 1^a of the drawing. These flanges 6^c are arranged to engage with the inner ends of the flange 1^c of the radiator frame 1, and are secured in place thereon by suitable fasteners 7. Thus the strengthening members are secured to the upper and lower tanks and are provided with means whereby the strengthened members are secured directly to the radiator frame, leaving the core unsecured to the strengthening means and thus relieving the strain which is incident to the removal of the radiator from its frame. The upper tank is held in place in the frame by suitable angular pieces 7", which are attached to the flange 1^c of the radiator frame 1 by fasteners 7'.

Thus, a very simple, but very efficient strengthening means for the radiator core is provided and the strain which is incident to the removal of the radiator from the radiator frame is not transferred to the core, and consequently all twisting of the core or breaking of the same will be obviated.

What I claim is:

1. In a radiator of the kind described, the combination with a radiator frame, of top and bottom tanks, a radiator core secured to said tanks and removable therewith from said frame, strengthening elements secured to said tanks and provided with flanges which snugly embrace, but are independent of the core, and means for securing the strengthening elements directly to the radiator frame.
2. In a radiator of the kind described, the

- combination with a radiator frame, of top and bottom tanks, a radiator core secured to said tanks and removable together therewith from said radiator frame, an inturned 5 stop flange at the front edge of said frame, channel-shaped reinforcing elements snugly embracing the core at its side edges and secured to the upper and lower tanks, the reinforcing elements being adapted to engage 10 the stop flange on the radiator frame, the said frame and reinforcing elements having rearwardly projecting flanges, and means for securing said flanges together.
3. In a radiator of the kind described, the 15 combination with a main frame, of top and bottom tanks and a radiator core secured thereto, and reinforcing elements which are distinct and independent of said core and main frame extending vertically between 20 and rigidly secured to said top and bottom tanks and spacing and tying the same together independently of the core, the said two tanks, core and reinforcing elements being removable together from said main 25 frame.
4. In a radiator of the kind described, the

combination with a main frame, of top and bottom tanks and a radiator core secured thereto, and reinforcing elements which are distinct and independent of said core and main frame and extend between and are rigid with said tanks at the side portions thereof so as to space and tie the same together, said tanks, core and reinforcing elements being removable together from the 30 main frame.

5. In a radiator of the kind described, the combination with a main frame, of top and bottom tanks and a radiator core secured thereto, and reinforcing elements which are 40 distinct and independent of said core and main frame, are rigidly connected to the tanks at the outer sides thereof and embrace the edges of the core, the said tanks, core and sub-frame being removable together 45 from the main frame.

In testimony whereof I affix my signature in presence of two witnesses.

JAMES W. CAIN.
